UNITED STATES PATENT OFFICE.

PETER AITCHISON, OF NEW ROCHELLE, NEW YORK, ASSIGNOR TO AMERICAN BANK NOTE COMPANY, OF NEW YORK, N. Y., A CORPORATION OF NEW YORK.

COLLECTING MECHANISM FOR PRINTED SHEETS.

Application filed August 10, 1921. Serial No. 491,149.

To all whom it may concern:

Be it known that I, PETER AITCHISON, a subject of the King of the United Kingdom of Great Britain and Ireland, residing at New Rochelle, in the county of Westchester and State of New York, have invented certain new and useful Improvements in Collecting Mechanisms for Printed Sheets, of which the following is a specification, reference being had therein to the accompanying drawings, which form a part thereof.

My invention relates to collecting mechanisms for printed sheets, and more particularly to a novel mechanism adapted to unwind a roll of continuous strip or web having wound therein dampened printed sheets and accumulating the sheets in a pile or stack so as to be in convenient form for the subsequent rapid feeding thereof to a printing press in making succeeding impressions, or transfer to the finishing room for trimming, numbering or for other purposes incidental to the completion of a printing job.

I have heretofore devised a process of treating printed dampened sheets which contemplates the winding of such sheets in a continuous strip or web of paper or other similar material coated or impregnated with cerasine, japan, paraffin, or other waxes or material having no affinity for the ink used in making an impression and substantially impermeable to air and moisture, so as to avoid the necessity for redampening the sheets for succeeding impressions and preserving the finish of the paper as well as preventing offsetting upon the strip or web.

Heretofore I have experienced difficulty in collecting the sheets thus wound in the strip or web, with sufficient rapidity and convenience to facilitate their subsequent handling either in feeding them to a press upon the making of another imprint, or for the finishing room, it having heretofore been necessary to remove the printed sheets from the strip or web and pile or stack them by hand. Such method of removal direct from the roll while feeding to a press, interferes with the routine handling of such sheets

and thus impairs the efficiency of the feeder. Furthermore, the feeder is ordinarily positioned well above the floor of the press room, and the organization of a press is such that the roll cannot be positioned convenient to the feeder so as to deliver the sheets one at a time with a rapidity commensurate with the feeding operation.

With these conditions in mind, I have devised a machine adapted to receive the roll of continuous strip or web and have it threaded therethrough to a rewind reel, so that by a mere unwinding operation, the printed sheets will be stripped directly from the strip or web and accumulated upon a collecting shelf in a stack or pile. In this manner the printed sheets may be rapidly removed from the roll of strip or web, and thus collected in a pile or stack sufficiently rapidly to avoid an exposure to the air for an interval which will tend to dry the paper appreciably, and without having the hand of an operator contact with each sheet. By utilizing the strip or web itself to convey the sheets directly to the collecting shelf, it is merely necessary to provide strippers which will separate the printed sheets from said strip or web to which the inked surface of the paper has a tendency to adhere. This means of transferring the printed sheet from the strip or web to the roll avoid the necessity for using delivery tapes and precludes possible wrinkling or distortion of the paper sheets.

The manner of unwinding and rewinding the strip or web not only results in the desired collecting of the sheets, but at the same time forms a reel of said strip or web after removal of the sheets so that it may be removed from the collecting machine and mounted directly in a press preparatory to receiving freshly printed sheets.

The invention consists primarily in a collecting mechanism for printed sheets embodying therein a collecting shelf, a guide roller adjacent and above said shelf about which a strip or web is adapted to pass, whereby printed sheets will be delivered di-

rectly from said strip or web to said shelf, 65
bearings for a roll of continuous strip or
web having printed sheets wound therein,
and a rewind reel adapted to receive said
strip or web after the printed sheets have
passed therefrom and been stacked or piled
upon the shelf; and in such other novel fea-
tures of construction and combination of
parts as are hereinafter set forth and de-
scribed, and more particularly pointed out
in the claims hereto appended.

Referring to the drawings,

Fig. 1 is a side elevation of a mechanism
embodying my invention; and

15 Fig. 2 is a plan view of a fragmentary
portion thereof adjacent the point of de-
livery of the printed sheet from the con-
tinuous strip or web to the collecting shelf.

Like numerals refer to like parts in both
20 of said views.

In the embodiment of my invention shown
in the drawings, the main frame of the ma-
chine is shown at 10, said frame at one end
thereof having offset brackets 11 supporting
25 one end of an inclined collecting or receiv-
ing shelf 12 provided with the usual stop
flange 13. The frame of the machine 10 is
free of obstructions between the side frames
which are properly positioned and held by
30 means of suitable stay rods 14.

Mounted between suitable bearing brack-
ets 15 and 16 carried by the brackets 11 re-
spectively, is a guide roller 17 of small
35 radius positioned between the collecting or
receiving shelf 12 and suitable bearings 18
on the frame 10 for a reel 19 containing a
roll of continuous strip or web having
wound therein sheets of dampened printed
paper 20 as shown upon the shelf 12. The
40 roller 17 is preferably positioned above the
bearings 18 so as to avoid too great an in-
clination of the strip or web between said
roller and the roll upon the reel 19 with
changes in the diameter of said roll with
45 the progressive actuation of the machine.
The reel 19 is removably mounted in the
bearings 18.

Carried by the frame 10 in any convenient
50 position are open bearings 21 adapted to re-
ceive a rewind reel 22, these bearings 21
being positioned upon the same side of the
roller 17 as the bearing 18, their location be-
ing somewhat a matter of choice and deter-
55 mined by the guiding mechanism for the
strip or web. Preferably the bearings 21
are located at the end of the machine oppo-
site to that where the shelf 12 is located,
suitable guide rollers 23, 24 and 25 being
60 arranged upon a frame 26 intermediate the
bearings 18 and 21.

The said guide rollers 23 and 25 are ar-
ranged upon a horizontal plane above the
axis of the bearings 18, the roller 24 being
positioned above the rollers 23 and 25. This

arrangement of rollers will relieve the strip 65
or web from stresses which would tend to
tear same or destroy the finish thereof, and
also will compensate in a measure for the
constant variance in the inclination of the
strip or web due to the change in diameters 70
of the rolls upon the reels 19 and 22.

Mounted upon brackets 27 upon opposite
sides of the machine adjacent and below
the guide roller 17 are a sequence of stripper
fingers 28, the ends of which terminate ad-
75 jacent, or bear lightly upon, the strip or
web passing about said guide roller. The
space between the brackets 27 is free of
obstructions aside from said stripper fingers
so as to provide clearance for the passage 80
of the sheets 20 along said fingers until they
are discharged upon the shelf 12.

Carried by the brackets 29 are slotted
guides 30 extending upwardly above said
brackets respectively, mounted in which 85
guides is a weighted roller 31 adapted to
continuously bear upon the surface of the
roll of strip or web upon the reel 22 while
permitting the gradual increase in the di-
ameter of this roll. Leading from adjacent 90
the top of the slot in the guides 30 is an in-
clined offset slot 32 adapted to receive the
arbors of the roll 31 and to hold said roll in
a position where it will not interfere with
the free mounting of the reel in, or the re-
moval of the filled roll from, the machine. 95

The arrangement of the guide rollers 17
and 23, above the bearings 18 and upon op-
posite sides thereof, will permit the utiliza-
tion of the lower circumference of the roll 100
upon the reel 19 as a guide for the strip or
web in passing through the machine, and
cause the portion of the strip or web engag-
ing the roll to assist in transmitting rotary
movement to said roll and reel, and as will 105
more fully appear hereinafter, will serve as
a keeper to retain the printed sheets upon
the strip or web until they reach the delivery
strippers 28.

The machine is operated by means of a 110
hand crank applied to the end of the reel 22,
or if desired, any desired means for me-
chanically rotating said reel may be sub-
stituted, the actuating means not being ma-
terial to the invention. The necessity for 115
the presence of an attendant and the avoid-
ance of excessively high speeds make the
method of application of power to the ma-
chine a matter of indifference, since it may
be hand-operated without substantial loss 120
of capacity.

The construction of the collecting or re-
ceiving shelf 12 is immaterial to the present
invention, and if desired any other desired
shelf may be substituted for that shown.

125 The operation of the herein described
mechanism is substantially as follows:—

The reel 19 containing a roll of continuous

strip or web of the character described, with the printed dampened sheets of paper wound therein, is removed bodily from the printing press where it constitutes a part of the delivery mechanism, and mounted in the bearings 18. The end of the web is then passed over the guide roller 17, brought downwardly between the brackets 15 and 16 and passed under the lower periphery of the roll 10 upon the reel 19, and about the guide rollers 23, 24 and 25 and fixed to the reel 22.

In this manner the reach 33 of the continuous strip or web which is drawn from the top of the roll upon the reel 19, serves to 15 convey the printed sheets 20 to the strippers 28. The sheets, by reason of their adhesion to the strip, will lay upon the outer surface of the reach 33 and thus be brought into the operative range of the grippers or pass 20 about the roller 17 in a relation thereto which will permit the removal of the said sheets from the strip or web.

By having the roller 17 of a short radius, there will be a sharp bend of the strip or web 25 adjacent the strippers 28 so that there will be a tendency of the edge of the sheet to separate from or spring away from the strip or web at this point, and thus avoid the necessity for the strippers bearing, with any substantial pressure, upon the strip or web, and even permit them to be spaced slightly away therefrom so as to avoid scraping of the surface of the strip or web thereby.

The under reach 34 of the strip or web 35 with the actuation of the machine will, through its engagement with the under circumference of the roll upon the reel 19, have a tendency to rotate this reel and thus relieve the strip or web in part of the longitudinal stresses particularly at the roller 17. At the same time it will prevent overrunning 40 of said reel 19 and will check any tendency of the printed sheets to separate therefrom, and thus cause them to follow the upper 45 reach 33 and be properly delivered to the shelf 12.

After leaving the roll upon the reel 19, the reach 34 is passed about the guide rollers 23, 24 and 25 and wound upon the rewind 50 reel 22 to which the actuating power for the machine is applied.

As heretofore stated, the positioning of the rollers 17, 23 and 25 in the manner described, will limit the angle of inclination of 55 the reach 33 between the roll and the guide roller 17, and the reach 34 between the roll upon the rewind reel and the guide roller 25.

The location of the roller 24 or the triangular relation of the rollers 23, 24 and 25 60 will avoid sharp bends in the strip or web except at the roller 17, and thus minimize likelihood of the cracking of the surface of the strip or web with a resultant weakening thereof and reduction in its life.

Since the roll upon the reel 22 is designed to be removed bodily therefrom and mounted in a printing machine, it is desirable to have this roll compactly wound, which result is secured by means of the floating weighted roller 31 bearing constantly thereon, guided in its outward movement by the slotted guides 30.

While there will be no offsetting of ink from the printed sheets to the treated strip or web, and while the entire sheet on both sides is dampened, which dampness permeates the body of the sheet sufficiently to make it limp when the sheet is properly mellowed, nevertheless experience has demonstrated that the freshly inked surface of the printed sheet will adhere to the strip or web while the opposite surface thereof will not so adhere. It is this condition which makes possible the construction of machine herein described.

As the sheets are collected in a pile or stack upon the shelf 12, they will fall perfectly flat, the dampness in the sheets while in the pile serving to preserve the mellow condition of the sheet so that thereafter no redamping is required by reason of the exposure of the sheets to the air during and after their removal from the roll.

It is good practice to keep the rolls of strip or web with the printed sheets therein intact until they are required for a succeeding impression so as to utilize the strip or web as a conditioning medium to prevent drying out of said sheets.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A collecting mechanism for printed sheets embodying therein a collecting shelf, a guide roller adjacent and above said shelf about which a strip or web is adapted to pass, whereby printed sheets will be delivered directly from said strip or web to said shelf, bearings for a roll of continuous strip or web having printed sheets wound therein, a rewind reel adapted to receive said strip or web after the printed sheets have passed therefrom and been stacked or piled upon the shelf, and means intermediate said bearings and said rewind reel whereby the lower reach of the strip or web, in its passage through the machine, is caused to engage the undersurface of the roll of continuous strip.

2. A collecting mechanism for printed sheets embodying therein a collecting shelf, a guide roller adjacent and above said shelf about which a strip or web is adapted to

4
 pass, whereby printed sheets will be delivered directly from said strip or web to said shelf, bearings for a roll of continuous strip or web having printed sheets wound therein, 5 a rewind reel adapted to receive said strip or web after the printed sheets have passed therefrom and been stacked or piled upon the shelf, and a guide roller mechanism positioned above the bearings for said roll of 10 continuous strip or web and intermediate same and said rewind reel, whereby said strip or web, after delivery of the printed sheet therefrom, will be caused to bear upon the lower portion of the strip or web upon 15 said roll.

3. A collecting mechanism for printed sheets embodying therein a collecting shelf, a guide roller adjacent and above said shelf about which a strip or web is adapted to 20 pass, whereby printed sheets will be delivered directly from said strip or web to said shelf, bearings for a roll of continuous strip or web having printed sheets wound therein, stripper fingers operative upon said strip 25 or web adjacent said guide roller and intermediate same and said delivery chute, a rewind reel adapted to receive said strip or web after the printed sheets have passed therefrom and been stacked or piled upon 30 the shelf and means intermediate said bearings and said rewind reel whereby the lower reach of the strip or web, in its passage through the machine, is caused to engage the undersurface of the roll of continuous strip.

35 4. A collecting mechanism for printed sheets embodying therein a collecting shelf, a guide roller adjacent and above said shelf about which a strip or web is adapted to 100 pass, whereby printed sheets will be delivered directly from said strip or web to said shelf, bearings for a roll of continuous strip or web having printed sheets wound therein, bearing brackets adapted to receive a 105 rewind reel, slotted guides extending upwardly above said brackets respectively, a weighted roller slidably mounted in said guides, whereby the strip or web will be compactly rewound upon said reel and means intermediate said bearings and said rewind reel whereby the lower reach of the strip or web, in its passage through the machine, is caused to engage the undersurface of the roll of 110 continuous strip.

40 45 5. A collecting mechanism for printed sheets embodying therein a collecting shelf, a guide roller adjacent and above said shelf about which a strip or web is adapted to 115 pass, whereby printed sheets will be delivered directly from said strip or web to said shelf, bearings for a roll of continuous strip or web having printed sheets wound therein, a 120 rewind reel adapted to receive said strip or web after the printed sheets have passed

therein, a rewind reel adapted to receive said strip or web after the printed sheets have passed therefrom and been stacked or piled upon the shelf, and three triangularly arranged guide rollers positioned above the bearings of said roll of continuous strip or 70 web and intermediate same and said rewind reel, whereby said strip or web, after delivery of a printed sheet therefrom, will be caused to bear upon the lower portion of said strip or web upon said roll, and sharp 75 bends in the strip or web adjacent said guide rollers, will be avoided.

6. A collecting mechanism for printed sheets embodying therein a collecting shelf, a guide roller adjacent and above said shelf about which a strip or web is adapted to 80 pass, whereby printed sheets will be delivered directly from said strip or web to said shelf, bearings for a roll of continuous strip or web having printed sheets wound therein, bearing brackets adapted to receive a 85 rewind reel, slotted guides extending upwardly above said brackets respectively, a weighted roller slidably mounted in said guides, whereby the strip or web will be compactly rewound upon said reel and means intermediate said bearings and said rewind reel whereby the lower reach of the strip or web, in its passage through the machine, is caused to engage the undersurface of the roll of 90 continuous strip.

7. A collecting mechanism for printed sheets embodying therein a collecting shelf, a guide roller adjacent and above said shelf about which a strip or web is adapted to 100 pass, whereby printed sheets will be delivered directly from said strip or web to said shelf, bearings for a roll of continuous strip or web having printed sheets wound therein, bearing brackets adapted to receive a 105 rewind reel, slotted guides extending upwardly above said brackets respectively, a weighted roller slidably mounted in said guides, whereby the strip or web will be compactly rewound upon said reel, and a 110 guide roller mechanism positioned above the bearings for said roll of continuous strip or web and intermediate same and said rewind reel, whereby said strip or web, after delivery of the printed sheet therefrom, will be 115 caused to bear upon the lower portion of the strip or web upon said roll.

8. A collecting mechanism for printed sheets embodying therein a collecting shelf, a guide roller of small diameter adjacent 120 and above said shelf about which a strip or web is adapted to pass with a sharp bend, whereby printed sheets will be delivered directly from said strip or web to said shelf, bearings for a roll of continuous strip or 125 web having printed sheets wound therein, a rewind reel adapted to receive said strip or web after the printed sheets have passed

therefrom and been stacked or piled upon the shelf and means intermediate said bearings and said rewind reel whereby the lower reach of the strip or web, in its passage through the machine, is caused to engage the undersurface of the roll of continuous strip.

5 In witness whereof I have hereunto affixed

my signature, in the presence of two subscribing witnesses, this 3rd day of August, 1921.
